United States Patent Office

Des. 218,107
Patented July 21, 1970

218,107

EXERCISING MACHINE

Jack Vincent Feather, 11293 Kerrigan Drive, Oakland,
Calif. 94605, and John W. Walker, 157 Clarence
Ave., Arroyo Grande, Calif. 93420

Filed Apr. 18, 1969, Ser. No. 16,809

Term of patent 14 years

Int. Cl. D21—03

U.S. Cl. D34—5

FIG. 1 is a perspective view of the exercising machine showing our new design;

FIG. 2 is a side elevation thereof;

FIG. 3 is a front elevation thereof;

FIG. 4 is a rear elevation thereof.

We claim:

The ornamental design for an exercising machine, as shown.
